UNITED STATES PATENT OFFICE.

ALFRED F. PAPIN, OF YONKERS, NEW YORK, ASSIGNOR TO CLAUDE A. PRAGER, OF NEW YORK, N. Y.

DESIGN FOR A TEXTILE FABRIC.

51,843.

Specification for Design.

Patented Mar. 5, 1918.

Application filed December 31, 1917. Serial No. 209,804. Term of patent 3½ years.

To all whom it may concern:

Be it known that I, **ALFRED F. PAPIN**, a citizen of the United States, residing at 31 Sherman avenue, Yonkers, N. Y., have invented a new, original, and ornamental Design for a Textile Fabric, of which the following is a specification, reference being had to the accompanying drawing, forming a part thereof.

The figure represents a front view of a piece of silk, cotton, or silk and cotton textile fabric, showing my design, the various

lines, dots, shaded portions, etc., each representing portions of the fabric of coloring different from other portions.

What I claim as new and desire to secure by Letters Patent, is:

The ornamental design for a textile fabric, substantially as shown and described.

ALFRED F. PAPIN.
